INLET FITTING FOR TANKS

Ernest Ephraim Rigby, Penwortham, Preston,
EnglandApplication September 20, 1945, Serial No. 617,480
In Great Britain September 20, 1944

3 Claims. (Cl. 4—41)

1

The present invention relates to improvements in inlet fittings for tanks of the type adapted to automatically allow water to pour into a tank from a water supply whenever the level of this is lowered, as for instance by the operation of a syphon.

In inlet fittings of this type in normal use the end of the water inlet pipe is adapted to be closed either by means of a spherical headed valve or by a rubber or leather disc carried in a piston head slideable in a cylindrical guide, an extension of the outlet end of the water pipe carrying at an offset point a pivot for a cranked lever for operating the valve and having a float at its opposite end.

An object of the present invention is to reduce the noise of valves of this type when tanks are filling.

According to the present invention a water inlet control valve for a water supply to a tank is provided with a water outlet preferably below the inlet to the syphon pipe and thus preferably below the lowest level of water in the tank, so that noise of water inflow into the tank is reduced to a minimum, a non-return air valve controlling a passage to the atmosphere from the water inlet pipe preventing syphoning back of water in the tank into the said supply pipe should pressure in this supply pipe fail.

The invention is further described with reference to the accompanying drawings, in which—

Fig. 1 is a sectional elevation through a flushing water tank,

Fig. 2 is a corresponding sectional elevation showing a modified form of valve as fitted to a flushing water tank,

Fig. 3 is an enlarged sectional elevation of a further modified form of non-return air valve as fitted to a flushing water tank.

In the drawings a tank 1 is provided with a water inlet pipe 2, the outlet 3 of which lies preferably below or substantially at the level of the inlet point 4 of the syphon pipe 5 of usual form disposed adjacent to the bottom of the tank, so that the outlet opening 3 from the water supply pipe is substantially at the level of the water remaining in the tank and thus noise of filling the tank is eliminated or becomes submerged almost immediately water enters the tank 1 after it has been emptied by syphonic action.

The opening 3 is controlled by means of a valve in the form of a ball 6 mounted on a spindle 7 pivoted at 8 to a lever 9 pivoted in turn at 10 to a bracket 11 which can be conveniently mounted on the elbow 12 connected to the water

2

inlet 2 and has a float 13 mounted on a rod 14 connected to it by pivot 15. Alternatively, the lever 9 and rod 14 may be made in one piece containing an elbow bend.

The valve 6 preferably seats upon a seating in the form of a moulded washer 16 of rubber or the like elastic material. The ball 6 may be loose and held in a cage to be displaced from its seating by a plunger.

10 In the construction of Fig. 1, in order to prevent syphoning back of water in the tank should the main supply in the pipe 2 fail, a non-return valve 28 is provided to allow air to enter the pipe 2, through a connection 29. At all other times the valve 28 is maintained on its seating by the water pressure.

15 In the construction of Fig. 2, instead of a ball such as 28, Fig. 1, a float 30 is provided in the vertical extension 31 of the elbow pipe 12 provided with a seating 32 so that when this pipe 12 is under water pressure there will be no escape of water past the valve 30.

20 Now it will be appreciated that very long periods of time may elapse during which the flushing system 1 is in general use before ever water supply in the pipe may fail, and thus the valve 28 (Fig. 1) or 30, 32 (Fig. 2) be called upon to operate, and that under such circumstances it may happen, unless other precautions are taken, that the valve 28 or 30, 32, respectively, may become stuck upon its seating, or, again, in the case of 30, 32, stick to the interior of the elbow tube 12, and be inoperative. In order, therefore, to ensure that this non-return relief valve will be 25 always ready to operate, means may be provided to trip it from its seating against the water pressure in the pipe 2 on each occasion that the flush tank is operated, as for instance by setting the syphon into operation by raising the plunger 33 30 by the usual lever 34. It will, of course, be appreciated that any other known method may be used of setting the syphon into operation for the emptying of the tank 1, the plunger 33 being indicative only of one of the well known types of 35 effecting this.

35 In the arrangement of Fig. 1 a lever 35 having a pin and slot connection 36 with the lever 34 carries at its opposite end a pin 37 which on each operation of the lever 34 abuts against the ball 28 to force it from its seating against the water pressure.

40 A small shield such as 38 may be provided to deflect any water which spurts up from the opening in the top of the casing for the ball valve 28 45 to direct this down again into the tank 1.

In the arrangement shown in Fig. 2 by way of example, the valve 30, 32, is tripped from its seating whenever the tank is flushed by syphonic action by means of a pin 39 on a bell crank lever 40 pivoted to a bracket 41 on the elbow tube 12, the opposite end 42 of which lever is within range of a projection 43 on the lever 9 connected to the ball 13. In other words, instead of tripping the safety relief valve from the lever 34 operating under syphonic action, this valve can be tripped from the float in the tank.

In the arrangement shown in Fig. 3, the pin 44 is made integral with the valve 28 and slides within an upstanding flange 45 disposed on top of the valve housing. A pin 48 is located beneath 15 and adjacent to the valve 28 to serve as a stop. A light umbrella shield 46 is mounted on the pin 44 by means of a screw 47 serving as an antisplash device.

In order to reduce wear on the valve 28, a washer 49 of resilient material is disposed between the valve 28 and the top of the valve housing.

Movement of the valve 28 is actuated by a lever 50, pivoted at 51 and having a projection 52 at its end remote from the valve 28 which is tripped by the water tank flushing lever 53.

I declare that what I claim is:

1. A flushing water tank including in combination a tank, a water supply pipe projecting into the tank and having its opening disposed substantially at the minimum level of the water in the tank, a float control valve controlling entry of water from said water supply pipe into the tank, a syphonic discharge means for water from said tank, means to put said syphonic discharge into operation, a connection on said water supply pipe communicating with the outside air, a valve on said connection normally sealing inlet of air thereto, and means to positively displace said valve from its seating whenever said tank is emptied by syphonic action.

2. A flushing water tank including in combina-

tion a tank, a water supply pipe projecting into the tank and having its opening disposed substantially at the minimum level of the water in the tank, a float control valve controlling entry of water from said water supply pipe into the tank, a syphonic discharge means for water from said tank, means to put said syphonic discharge into operation, an air inlet connection on said water pipe, a valve on said connection normally closing entry of air to said pipe, means to operate said syphonic action, and means operated thereby to displace the valve from its seat to prevent syphoning back of water in the tank into said supply pipe.

3. A flushing water tank including in combination a tank, a water supply pipe projecting into the tank and having its opening disposed substantially at the minimum level of the water in the tank, a float control valve controlling entry of water from said water supply pipe into the tank, a syphonic discharge means for water from said tank, means to put said syphonic discharge into operation, a connection on said water supply pipe to the outer air, a valve on said connection to prevent syphoning back of water in the tank into said supply pipe should pressure in this supply pipe fail, and means connected to said float operated valve to displace said air valve whenever said float operated valve is displaced from its seating.

ERNEST EPHRAIM RIGBY.
